UNITED STATES PATENT OFFICE.

WILLIAM T. MCKINSTER, OF MATTIE, KENTUCKY.

DESIGN FOR A MAIL-BAG.

SPECIFICATION forming part of Design No. 32,376, dated March 20, 1900.

Application filed February 15, 1900. Serial No. 5,385. Term of patent 7 years.

To all whom it may concern.

Be it known that I, WILLIAM T. MCKINSTER, a citizen of the United States, residing at Mattie, in the county of Lawrence and State of Kentucky, have invented and produced a certain new and original Design for Mail-Bags; and I do declare the following to be a full, clear, and exact description of the invention, such as will enable others skilled in the art to which it appertains to make and use the same.

The invention relates to a new and original design for mail-bags; and it consists of a design of the configuration shown in the accompanying drawing, in which I have represented my invention in perspective.

The leading feature of the design comprises

the body portion 1, the bottom of which is arched, as shown at 2, thence extends downwardly, as shown at 3, and thence formed with two outwardly-curved bulges, as shown at 4, which terminate in a vertically-disposed bulge 5.

What I claim is—

The design for a mail-bag, as herein shown and described.

In testimony whereof I have hereunto set my hand in presence of two subscribing witnesses.

WILLIAM T. MCKINSTER.
